UNITED STATES PATENT OFFICE.

THOMAS EUBANK, OF LITTLE ROCK, ARKANSAS, ASSIGNOR TO THE MISSOURI RAILWAY EQUIPMENT COMPANY, OF ST. LOUIS, MISSOURI.

DESIGN FOR A JOURNAL-BOX.

SPECIFICATION forming part of Design No. 26,514, dated January 12, 1897.

Application filed November 23, 1896. Serial No. 613,207. Term of patent 14 years.

To all whom it may concern:

Be it known that I, THOMAS EUBANK, a citizen of the United States, residing at the city of Little Rock, in the county of Pulaski, State 5 of Arkansas, have invented a new and original Design for Journal-Boxes, of which the following is a full, clear, and exact description, reference being had to the accompanying drawings, forming a part of this specification, wherein—

Figure 1 illustrates a side elevational view of a journal-box embodying my design. Fig. 2 is a perspective view of a journal-box ornamented and configured according to my new 5; design.

This invention relates to a new and original design for journal-boxes; and it consists in the shape and configuration illustrated in the drawings and hereinafter fully described.

In the drawings, A indicates the side wall, on the outer face of which is formed a vertically-disposed elongated projection a, which is substantially semicircular in form. An opening a' is formed in the side wall A, to the rear of projection a and slightly above the horizontal center of the box. A projection or rib a² is formed just to the rear of opening a', the front face of which rib is flush with the rear wall of opening a'.

In the above description I have referred to 30 but one side wall, it being understood, of course, that both side walls are substantially alike.

B indicates two ribs transversely disposed across the top of the box, the adjacent faces 35 of said ribs being perpendicular, while their outer faces are curved, as shown.

The rear end of the top wall is raised, as shown, forming a shoulder B'.

The mouth or opening at the front of the 40 box is arranged at an incline, while its throat portion is curved, as shown.

C indicates the rear wall of the journal-box, which is formed with an elongated opening C', said opening being vertically disposed and 45 curved at its ends, as shown.

The essential feature of my design resides in the openings in the side walls of the box.

What I claim is—

The design for journal-boxes, substantially 50 as herein shown and described.

In testimony whereof I hereunto affix my signature, in presence of two witnesses, this 14th day of November, 1896.

THOS. EUBANK.

Witnesses:

PATRICK McDOWELL,
WALTER ABINGTON.
